COMBINED FILTER AND PRIMER FOR OIL BURNERS

Melvin C. Bennett, Middletown, Conn., assignor of one-half to Thomas F. Smithwick, Middletown, Conn.

Application August 16, 1935, Serial No. 36,534

3 Claims. (Cl. 158—36)

This invention relates to new and useful improvements in liquid fuel burner equipment and has particular reference to a combined filter and primer for oil burners.

5 An object of the invention is to reduce the fire hazard connected with oil burners by preventing flooding or running over of the burners.

Another object is to provide means for delivering a predetermined priming charge to a burner 10 when it is desired to light the latter, whereby it is not necessary for the operator to stand about and watch the burner and guess when it has the proper priming charge.

15 A further object is to provide a means having the characteristics indicated and which also includes a filtering feature whereby the oil or other liquid fuel is filtered before being permitted to reach the burner.

20 Other objects and advantages will become apparent from a consideration of the following detailed description taken in connection with the accompanying drawing wherein a satisfactory embodiment of the invention is shown. However, it will be understood that the invention 25 is not limited to the details disclosed but includes all such variations and modifications as fall within the spirit of the invention and the scope of the appended claims.

In the drawing:

30 Fig. 1 is a side elevational view with parts broken away and showing the present filter and primer associated with a fuel supply and a burner;

35 Fig. 2 is an enlarged view partly in side elevation and partly in section showing the present filter and primer; and

Fig. 3 is a transverse section substantially on line 3—3 of Fig. 2.

40 Referring in detail to the drawing at 5 is generally indicated an oil burner of the kind commonly used in kitchen ranges, although in the drawing the burner is not shown in place in the fire box of a range. The burner comprises a base 6 having an annular groove 7 in which is located any or the usual wick 8, and supported by the base 6 and extending upwardly from the inner and outer sides of the wick are any or the usual inner and outer concentric perforated cylinders 9. As here shown the burner is carried by 45 an upright 10 supported by any desired base means 11.

50 Fuel is supplied to the burner from any suitable source such as the bottle 12, commonly employed for this purpose, and the bottle discharges 55 into a constant level fuel supply chamber 13

carried by an arm 14 adjustable vertically on an upright 15 extending from a supporting base 16. A set screw or other means 17 is carried by the arm 14 and after the arm is adjusted to the desired position said set screw is tightened or 5 screwed in against the upright 15 to hold the arm and the chamber 13 in the adjusted position. The supporting base 16 includes radially extending arms through the outer ends of which are threaded screws 18 adapted to be adjusted to level 10 the base and have the upright 15 extend truly vertically.

As is the usual practice the bottle 12 is held in inverted position with its neck or discharge end located within the chamber 13 and spring 15 arms or the like 19 may be used for holding the bottle in position. These arms are carried by portion 20 vertically adjustable on the upright 15 and a set screw 21 is provided to be threaded against the upright whereby to hold the portion 20 in the arms 19 in the proper adjusted position. On the neck of the bottle there is threaded 25 a metal cap 22 having a central discharge opening which is automatically closed by a spring operated valve 23 when the bottle is removed from the supporting stand but which is held open by the end of the valve stem resting on the bottom of the oil chamber for the escape of oil when the bottle is positioned as shown in Fig. 1.

30 A stem 24 is secured to the valve and extends with a suitable clearance through the opening in the cap 22 and at its outer end is provided with a head 25 and about such stem between the head and the cap 22 there is located a coil spring 26. Between the spring and the head 25 35 there is arranged a member 27 which may be U-shaped or which may have openings in its side walls and which is movable with the stem 24 and relative to the cap 22. When the bottle is inverted and its neck placed in the chamber 13 the member 27 seats on a raised annular portion 28 in the bottom of the chamber and owing to the weight of the bottle and its contents the cap 22 seats against said member whereby the latter is supporting the weight of the bottle and 40 its contents. At this time the valve 23 is lifted and the spring 26 is compressed due to the abutment of the valve stem head 25 with the bottom 45 wall of the chamber 13.

With the valve open the oil or other fuel 50 flows from the bottle into the chamber 13 until its level in such chamber is sufficient to seal the outlet or delivery opening through the bottle cap 22. However, on the bottle being lifted off the stand or sufficiently to permit the spring 26 to 55

expand to normal condition the latter shifts the valve 28 into position closing the outlet or discharge opening of the cap 22 and at the same time the spring moves the member 27 outwardly 5 with respect to the cap. For refilling of the bottle 12 the cap 22 is arranged to be threaded onto and off the bottle neck. In the drawing the level at which the fuel in the chamber 13 seals the discharge opening in the cap 22 is indicated 10 by the broken line 29. As this line is followed across the drawing, it will be noted that such level on the burner 5 indicates the highest level which fuel should be permitted to reach in the burner.

15 When making an installation an effort is always made to so adjust the chamber 13 with respect to the height of the burner that the discharge opening through the cap 22 of the bottle will remain sealed to prevent the further discharge 20 of fuel oil while the fuel oil in the chamber 13 is at a level equal to the high level the fuel should be permitted to reach in the burner. Thus in a proper installation on the oil reaching a predetermined level in the burner the further discharge 25 of oil from the bottle is prevented until some of the oil in the burner is consumed whereupon additional oil will be drained from the chamber 13 to the burner and additional oil from the bottle will be fed into the chamber to again raise the 30 level of the supply therein.

It not infrequently happens that the chamber 13 is located too high with respect to the height of the burner and that if the usual fuel valve between the supply and burner is open without 35 the burner being lit the latter will be flooded. With the usual arrangement when the burner is to be ignited the fuel valve is opened and then the operator must stand about for a few minutes until a priming charge of fuel reaches the burner.

40 Usually a guess is made as to when the proper priming charge has reached the burner. If the oil level in the supply chamber 13 is too high with respect to the burner and the operator waits too long before lighting it the burner is likely to 45 be flooded or to overflow permitting oil to spill into the fire box of the range. This creates a serious fire hazard when the burner is lighted.

The present invention provides means whereby 50 the oil delivered to the burner is filtered and whereby when the burner is to be ignited only a definite predetermined quantity of fuel oil, comprising the proper priming charge, will be delivered to the burner and whereby it will be unnecessary for the operator to stand about and 55 watch the burner and then guess as to when it has received the proper priming charge. Such means comprises a receptacle generally designated 30, and at one side provided with a lug or extension 31 having an opening through which 60 the upright 15 passes whereby the receptacle may be adjusted vertically on said upright and a set screw 32 carried by said extension is adapted to be threaded against the upright so as to support the receptacle in the proper position of vertical 65 adjustment.

Internally the receptacle 30 is divided into a relatively deep receiving and settling chamber 33 and a priming or discharging chamber 34 the bottom wall 35 of which is preferably located 70 above the bottom wall 36 of the chamber 33. The chambers are separated by a wall 37 which in its lower portion, just above the bottom wall 35 of the priming chamber, is provided with an opening in which is located a screen 38. If desired screen 38 may be omitted and a screen may

be provided across the chamber 33 at or below the level of the bottom wall of the priming chamber, and in some cases both screens may be used.

By means of a conduit 39 fuel is taken from the lower end of the chamber 13 and delivered 5 to the receiving chamber 33 of the receptacle 30. The conduit is connected with the receptacle by a suitable fitting 40 located so that the fuel enters the chamber 33 above the bottom thereof. In the drawing the low level line for the burner 10 is indicated by the broken line 41 and it will be noted that the same is just above the bottom wall 35 of the priming chamber 34. As the height of the fuel oil increases in the chamber 33 to a point beyond the level indicated by the line 41 15 fuel oil flows through the screen 38 into the chamber 34 and the fuel oil in both the chambers 33 and 34 will rise to the level indicated by the broken line 29. A conduit 42 connects the priming chamber 34 with a fitting 43 discharging into 20 a short tube 44 entering the lower end of the groove 7 of the burner.

In the conduits 39 and 42 there are arranged hand cut-off valves 45 and 46 respectively. With the parts installed as shown when the valves 45 25 and 46 are open oil will flow from the bottle 12 through chamber 13 and receptacle 30 to the burner. In the receptacle the oil will be delivered to chamber 33 and from the latter will move to the upper or priming chamber 34 and thence 30 to the burner. Dust or other foreign matter will be caught by the screen 38 and prevented from reaching the burner and will settle in the bottom portion of the chamber 33. Also, any water in the oil will gravitate to the bottom of the chamber 35 and such foreign matter may be drained off through a petcock 47. A cover 48 closes the upper ends of the chambers 33 and 34 to exclude dust.

Assuming that the apparatus is set up as indicated, before the burner is ignited the valve 46 40 is closed and the valve 45 is opened. This permits the fuel to rise to the proper predetermined level in the priming chamber 34. Now, when the burner is to be ignited the valve 45 is closed, and the valve 46 opened. Thus fuel is prevented from moving from the bottle 12 to the receptacle 30 and a predetermined priming charge will be drained from the receptacle to the burner. The size and relationship of the parts is such that the oil in the chamber 34 together with that portion 50 of the oil in chamber 33 above the broken line 41 constitutes a priming charge of the proper size and as such will be drained into the burner.

Owing to the fact that the valve 45 is closed the oil drained into the burner from the receptacle 30 will not be replenished by additional oil taken from the bottle or from the supply chamber 13. Therefore, only a definite predetermined priming charge will be delivered to the burner and it will not be necessary for the operator to 55 make a guess as to when the proper priming charge has been delivered to the burner, and further it will not be necessary for the operator to stand around and wait for the charge to reach the burner in order that she may be on hand to prevent flooding of the burner. After the burner is primed and ignited the operator opens the valve 45 and the fuel will be fed the burner in the usual manner.

With the described apparatus it will be apparent that irrespective of whether or not the supply chamber 13 is at the proper elevation with respect to the burner only a definite priming charge will be delivered to the burner on closing 70 of the valve 45 and opening of the valve 46. The 75

- cover 48 does not absolutely seal the upper end of the receptacle 30 so that the apparatus will not become air bound. By adjusting the receptacle vertically relative to the chamber 13 or by adjusting said chamber relative to the receptacle the height to which fuel may rise in the priming chamber 34 may be adjusted so as to have such chamber receive the desired priming charge. When the burner is to be extinguished the valve 10 46 should be closed and the valve 45 left open to insure the presence of a priming charge in the upper portion of the receptacle 30 so that when the burner is to be again started the proper priming charge will be delivered on closing of the valve 15 45 and opening of valve 46.

It is important that the entrance to the discharge or outlet pipe 42 be substantially at the normal liquid level as I have found this effects a material saving in oil consumption.

- 20 I have also found this device gives a more uniform operation for the burner. The filter with the settling and primer chamber acts as a resistance unit so that the fuel feeds slower and at a more uniform rate and prevents overloading of 25 the burner. The burner does not fluctuate when the bottle feeds as is common with ordinary feeds. Also, the oil does not feed from the bottle as long as each feeding when this device is used thus giving a more uniform and constant feed with less 30 fluctuation at the burner.

In the receptacle or bottle base 13 I prefer a head of about one inch between the normal fuel level 29 and the entrance to pipe 39 with a diameter of four or five inches for said bottle base. The 35 fuel passes upwardly in the chamber 33 of the filter device and then flows slowly from the primer chamber 34 at the normal fuel level with practically no head to the burner. As indicated this arrangement gives a more uniform feed with less 40 fluctuation and no overloading of the burner, resulting in more uniform and efficient operation of the burner with less fuel consumption as it is utilized more effectively and more efficiently.

Having thus set forth the nature of my invention, what I claim is:

- 45 1. A fuel feeding system for a liquid fuel burner comprising a bottle base providing a constant level supply chamber for an inverted bottle feed and for determining the highest level to 50 which fuel may rise in the burner, a receptacle between the supply chamber and the burner, a conduit connecting the supply chamber with the receptacle, a manually operable shut off valve between the supply chamber and the receptacle,

a conduit connecting the receptacle with the burner and connected to the receptacle at a point below the high fuel level to determine the low fuel level in the burner, said receptacle having sufficient capacity between said levels to supply 5 a sufficiently large priming charge to the burner for starting it when said shut off valve is closed, and a second shut off valve between the receptacle and the burner.

2. A fuel feeding system for a liquid fuel burner 10 comprising a constant level supply chamber for determining the highest level to which fuel may rise in the burner, a receptacle between the supply chamber and the burner including a receiving and settling chamber and a priming chamber 15 communicating with the latter chamber, a conduit connecting the supply chamber with the receiving chamber at the lower part thereof, a manually operable shut off valve in said conduit, a conduit connecting the priming chamber with 20 the burner and connected with the priming chamber at a point below the high fuel level to determine the low fuel level in the burner, said receptacle having sufficient capacity between said levels to supply a sufficiently large priming charge 25 to the burner for starting it when the shut off valve is closed, a second shut off valve between the receptacle and the burner, and means for mounting said devices for relative vertical adjustment whereby to adjust said fuel levels. 30

3. A fuel feeding system for a liquid fuel burner comprising a bottle base providing a constant level supply chamber for an inverted bottle feed and for determining the highest level to which fuel may rise in the burner, a receptacle between 35 the supply chamber and the burner and including a receiving and settling chamber, a conduit connecting the supply chamber to the lower part of the receiving chamber, a manually operable shut off valve in said conduit, a conduit connecting the receptacle with the burner and connected with the receptacle at a point below the high fuel level to determine the low fuel level in the burner, said receptacle having sufficient capacity between 40 said levels to supply a sufficiently large priming charge to the burner for starting it when the shut off valve is closed, a second shut off valve between the receptacle and the burner, an upright standard, and means for mounting the supply chamber and the receptacle for relative vertical adjustment on the standard whereby to adjust said fuel levels. 45
